MACHINE AND METHOD FOR MAKING
KNITTED FABRIC

Albert E. Page and Frank R. Page, Brooklyn,
N. Y., assignors to Scott & Williams, Incorporated,
New York, N. Y., a corporation of Massachusetts

Application April 8, 1936, Serial No. 73,376

15 Claims. (Cl. 66—9)

This invention relates to circular knitting machines, the method of operating the same and the product produced thereby and more particularly to such machines, method and product when an elastic yarn is fed as an additional yarn during the operation of the machine and it is an object of this invention to provide a simplified and improved mechanism for incorporating an elastic yarn in a fabric; to provide an improved method for combining the rubber yarn with the loops of the fabric during the knitting thereof; and to provide an improved fabric and particularly fabric in the form of a completed stocking.

15 In the drawings—

Fig. 1 is a view in elevation of the upper portion of a circular knitting machine of the Scott and Williams type embodying this invention, only such parts thereof being shown as are necessary to illustrate the invention;

20 Fig. 2 is a horizontal sectional view showing in plan certain of the needle operating cams and their operating means;

Fig. 3 is a horizontal sectional view showing in plan parts of the needle jack selecting and operating means;

25 Fig. 4 is a partial top plan view showing the operating means for the rubber yarn guide and a sinker operating cam;

30 Fig. 5 is a fragmentary view in elevation showing the operating means for the make-up selector lever;

35 Figs. 6 to 10, inclusive, are views in elevation showing pattern drum cams for controlling various operations of the machine, Figs. 6 and 7 showing cams for controlling the rubber yarn guide and the cutter and clamp for the rubber yarn where the cutter and clamp are used, Figs. 8 and 10 showing cams for controlling the operation of the needle operating cams; and Fig. 9 showing the cam for controlling the rubber yarn guide when the cutter and clamp are not used;

40 Fig. 11 is a diagrammatic view showing the needles and their jacks and operating cams developed into the plane of the paper, the parts being positioned as at the completion of the selvage, the cutter and clamp for the rubber yarn not being used and the body yarn being omitted for clearness;

45 Fig. 12 is a partial view similar to Fig. 11 and showing the relation of the rubber yarn guide and needles at the time the rubber yarn is inserted;

50 Fig. 13 is a view similar to Fig. 11, the parts

being positioned as when the interlacing of the rubber yarn with the needles is begun;

Fig. 14 is a view similar to Fig. 12 and showing the relation of the rubber yarn, guide and needles upon the introduction of the rubber yarn 5 when the cutter and clamp for the rubber yarn are used;

Fig. 15 is a diagrammatic view in plan showing the relations of the rubber yarn, needles and transfer bits at the introduction of the rubber 10 yarn where the cutter and clamp for the rubber yarn are not used, the body yarn being omitted for clearness;

Fig. 16 is a view similar to Fig. 15 showing the relations at the throat plate in the course after 15 that shown in Fig. 15;

Fig. 17 is a diagrammatic view showing the relation of the rubber yarn at its introduction to the loops of the body yarn at the throat plate;

Fig. 18 is a plan view of a portion of a stocking 20 welt fabric showing the relation of the rubber yarn to the loops of the body yarn;

Fig. 19 is a view in elevation of the portion of fabric shown in Fig. 18;

Fig. 20 is a plan view of a portion of a stocking 25 fabric showing the relations of the yarns in the courses adjacent the transfer course which marks the completion of the welt;

Fig. 21 is a view similar to Fig. 15 showing the relation of the parts during the transfer of the 30 loops of the welt from the transfer bits to the needles;

Fig. 22 is a view in elevation of the parts shown in Fig. 21;

Fig. 23 is a diagrammatic plan view showing the 35 relation of the rubber yarn in the transfer course to the loops of the body yarn during transfer;

Fig. 24 is a view in elevation of the parts shown in Fig. 23;

Fig. 25 is a diagrammatic plan view of a portion of the needle circle showing the relation of the sinkers and the needles during the measuring of the elastic yarn on the sinkers in the knitting of the stocking top;

Fig. 26 is a developed view in elevation showing 45 the needle yarn drawing operation corresponding to the sinker measuring operation of Fig. 25;

Fig. 27 is a diagrammatic plan view of another portion of the needle circle showing the interlacing of the elastic yarn and the slackening of 50 certain loops of the inelastic or body yarn during the knitting of the top;

Fig. 28 is a developed view corresponding to Fig. 27 showing the interlacing of the yarns at the knocking-over point; and

Fig. 29 is a partial view, drawn to an enlarged scale, in vertical section, of a stocking welt and top constructed in accordance with this invention and showing the relation of the rubber yarn to the loops of the body yarn in the welt and top.

In the drawings the invention is shown in connection with a Scott and Williams circular knitting machine arranged for knitting stockings of plain fabric and having an integral turned welt formed during the manufacture with a selvage or beginning edge automatically knit by the machine at the beginning of the welt, such a machine being shown in the patent to Robert W. Scott No. 1,282,958, issued October 29, 1918.

In the drawings in which only such parts of the machine are shown as are necessary to illustrate the invention there is shown the needle cylinder 260, of such length as to accommodate both needles N, intermediate jacks 380 and pattern jacks 381 for the needles, the cylinder 260 being arranged for rotation in the bedplates B and B' and being driven as shown in the Scott patent referred to above. The machine is also provided with the usual sinker plate 285 and cam cap 300 therefor. Also forming part of the machine is a dial D which supports the transfer elements or bits T, as shown in Figures 15, 16 and 21, the dial being rotated and the transfer elements operated as shown in the patent referred to.

To operate the needles there is provided the usual knitting cams 361, 357 and 360 which function in the usual manner. There is also provided draw-down cams 382 and 12 and a raising cam 12^a which cooperate with the butts on the needles for the operation of the needles. For the operation of the jacks which serve to position the needles for operation by their cams there are provided a jack operating cam 386 and a cam 100 which engages the upper portion of the jacks so as to force outwardly the lower portions thereof in position to be engaged by either the make-up selector lever or cam 102 or any of the reader cams 765 which are operated from the trick wheel or auxiliary pattern drum 106 with which this machine is equipped. The pattern drum 106 is operated in the usual manner by a pawl 105 which engages the teeth 104 on the drum 106, the operation of the reader cams being as is shown in the patent to Page and Swinglehurst, No. 1,906,204, dated April 25, 1933. The various yarns, with the exception of the rubber yarn, are fed to the needles by the usual yarn fingers operated by push-rods from the main pattern drum in the usual manner. To supply the rubber yarn to the needles there is provided a rubber yarn guide 110 slidably mounted on the bracket 112 which serves to support the driving means for the dial, said yarn guide being biased to its lower or yarn introducing position by a spring 114 secured to the bracket 112 and to the upper end of the yarn guide 110. To raise the yarn guide from operative position there is provided a bell crank lever 116 pivotally mounted on the bracket 112 and having an end of one arm thereof engaged beneath a pin 111 secured in the yarn guide 110. Through the end of the other arm of the bell crank lever 116 one end of link 118 extends, the other end of the link being secured in an opening in a yarn finger F' one of the usual yarn fingers not otherwise used at this time. A collar 118^a, fixed on the link 118, causes the bell crank lever 116 to be operated with the link 118 as the link is drawn down by movement of the yarn finger F', the yarn finger being operated by a push rod 460 from a cam 122 on the main pattern drum 120. The cam 12 is mounted upon a carrier 384 which is slidably mounted in a bracket 386 secured to the base plate B. A spring (not shown) biases the cam and slide to their outer or inactive position and the cam is moved inwardly to its operative positions by a lever 200 which has an end carrying a bolt or pin 204 which engages the carrier 384 and is secured in adjusted position in the lever by the nut 202 while the opposite end of the lever 200 is provided with a contact face 206 positioned to be engaged by a cam 462^a fixed on a push rod 462. The adjustment of the nut 202 on the bolt 204 provides a means for adjusting the position to which the cam 12 is moved. The push rod 462 is operated from a cam 124 on the main pattern drum 120 which cam is provided with contact surfaces at different elevations so as to provide for the stepped elevation of the push rod 462 and the stepped operation of the cam 12 by the inclined surface 20 of the cam 462^a. The cam 12^a which is carried by a slide 384 mounted in the bracket 386 is also operated from the slide 384 by means of a spring plunger 383 mounted in a lateral extension 384^a of the slide 384 but its inward movement is limited by a stop 385 so that it can move inwardly only far enough to engage the long butt needles. Thereafter movement of the slide 384 is permitted by the spring through which the slide operates the cam 12^a. The cam 12^a is so positioned with respect to the cam 12 that the movement of the push rod 462 from the face of the drum 120 to the first level of the cam 124 permits of the cam 12^a occupying its position to engage the butts of the long butt needles n' before the cam 12 is moved inwardly far enough to engage such long butts. The cam 12^a is also moved to its outer position by a spring (not shown). Movement of the pattern drum 106 so as to place the intermediate level of the cam 124 beneath the push rod 462 brings the cam 12 into position to engage the long butt needles n' while the cam 12^a is restrained by its stop from moving inwardly further. Movement of the drum 106 to place the push rod 462 upon the outer level of the cam 124 permits of the cam 12 being moved inwardly to engage the short butt needles n² as well as the long butt needles whereby all the needles are operated, the cam 12^a being still restrained from further inward movement. At its upper end the push rod 462 is provided with a pin 462^b which engages the outer end of a lever 210, pivotally mounted on the pin 552 on which the latch guard ring 550 is pivoted. The inner end of the lever 210 is provided with a housing for a spring-pressed plunger 212 which bears upon the free end of a lever 214, the other end of which is pivotally mounted at 216 upon a standard carried by the bedplate B. Intermediate its length, the lever 214 is provided with a housing 216^a for a spring-pressed plunger which plunger serves to hold the lever 214 in raised position until operation of the push rod 462 causes the lever 214 to be depressed. Secured to the lever 214 is a cam 189 which serves to operate the sinkers w.

The cam 382 is slidably mounted in a housing 388 secured to the bedplate B and is biased to its outer position by a spring, not shown. To press the cam 382 to its inner position there is provided a lever 220 pivotally mounted, as at 222, on the bedplate B and having one arm thereof engaged with the adjustable abutment 223 secured to the outer end of the cam 382 while the other end of the lever 220 is positioned to engage a cam 461^a secured on a push rod 461. The cam

461^a has a stepped contact surface so that upon operation of the push rod 461 by the cam 126 on the main pattern drum 120 the push rod 461 may be positioned with the end of the lever 220 in engagement with one or another of the different portions of the contact surface, the cams being arranged on the push rod 461 and the pattern drum 120 so that when the push rod 461 is in contact with the surface of the pattern drum 120 the lever 220 is engaged by the upper contact surface of the cam 461^a and the lever 220 is positioned so that the cam 382 is withdrawn from engagement with the needle butts and is in its outer or inoperative position. When the push rod 461 is on a cam face of cam 126 of intermediate height the push rod is elevated to bring the center contact face of the cam 461^a in engagement with the lever 220 and the cam 382 is moved inwardly to a position in which the long 20 butt needles are engaged and when the push rod 461 is on the outer contact surface of the cam 126 the push rod is raised to a position in which the lowest contact face of the cam 461^a is in engagement with the lever 220 and the cam 382 is moved inwardly to a position in which it engages 25 both the short butt and long butt needles.

A clamp and cutter mechanism 230 is operated by a lever 232 pivotally mounted on the standard 557 on the latch guard ring 550 against the action 30 of a spring 231. The lever 232 projects beyond the standard 557 and at its outer end it has a pin 233 engaged by the upper end of a push rod 464 which is operated by the cams 123 and 123^a on the pattern drum 120. Pivotally mounted on a standard 236 supported from the baseplate B' is a lever 238 having a pin 238^a mounted in the end thereof and provided with an opening through which extends one end of a rod 240. Fixed to the lever 238 is a projecting finger 239 positioned to be engaged by a cam 462 fixed on the push rod 462. On the rod 240 adjacent the pin 238^a is fixed a collar 241 arranged to be engaged by the pin 238^a and held in contact therewith by a spring 242 which extends between the collar 241 and the push rod 462. The opposite end of the rod 240 engages in an opening at the outer end of a cam 244 pivotally mounted on the baseplate B' and positioned so that when the push rod 462 is raised the cam 244 engages with the butts of the jacks being raised by the cam 366 to force the butts of the jacks from the cam so as to limit the distance to which the jacks are raised by the cam 366. The make-up selector lever 102 is pivotally mounted, as shown in Figure 3, on the pin 246 on which the reader cams 166 55 765 controlled by the auxiliary pattern drum 106 are also pivotally mounted. The make-up lever 102 is operated to a position in which it engages butts on the jacks by a crank arm 248 fixed on a shaft 250 which is operated by crank arm 252 also fixed on the shaft 250 and positioned to be engaged by a cam 130 on an end of the main pattern drum 120. A spring, not shown, biases the lever 102 to its inoperative position.

65 The cam 189 which is attached to the lever 214 is positioned, as shown in Fig. 25, to engage the butts of all sinkers to withdraw the sinkers so that as the rubber yarn R is drawn down by the needles as they are engaged by the cam 12 the elastic yarn passes below the nebs of the sinkers and the loops are drawn over the knocking-over ledges of the sinkers. The sinkers are returned to normal position by the fixed沉器 cam 198 so that the bights of the rubber yarn drawn 70 75 are taken into the throats of the sinkers and the

elastic yarn is kept from being raised as the needles are subsequently raised to take the body yarn. The loops drawn by the needles determine the length of the rubber yarn drawn and consequently the contracted width of the stocking top. This width may be varied by varying the length of the loops drawn by the needles. 5

In practice the cams are positioned to operate the needles to draw an excess of yarn and the fabric is reduced to the desired width by adding 10 tension on the rubber yarn.

In order to obtain a clearly defined ribbed appearance the sinkers on each side of the tying needles are operated inwardly earlier and to a greater extent at the knitting point than are the other sinkers so as to lengthen the loops at the wales where the elastic yarn passes through, the sinkers being moved inwardly just as the tying needles approach the bottom of their movement under the leading stitch cam 361. The sinkers thus operated are provided with long butts 389 and are operated by a special sinker cam 312 pivotally mounted in the sinker cam cap 300 and which may be controlled as shown in the patent to Robert W. Scott, No. 1,189,220, dated June 27, 1916. The sinkers with the short butts 400 are operated at the usual time for the usual distance by the regular sinker operating path in the sinker cam cap 300.

While the machine has been shown equipped 30 with a cutter and clamp mechanism for the rubber yarn it is possible to operate the machine without this cutter and clamp, in which case the rubber yarn extends continuously from stocking to stocking. Where the cutter and clamp are 35 not used the cam 122^a, shown in Fig. 9, on the pattern drum 120 which operates the push rod 460 controlling the rubber yarn guide 110 is somewhat shorter than the cam 122 which operates the push rod 460 when the cutter and clamp are 40 used but, except for the difference in length, this cam 122^a is the same as cam 122 and the rubber yarn extends from the yarn guide 110 under the dial D and through the needle cylinder to the stocking which has been pressed off and is not 45 held by the cutter and clamp.

On the press-off rack which withdraws the body yarn from the needles so as to press-off the completed stocking cams are positioned for raising every other needle in preparation for the 50 make-up of the stocking about to be started. This selection of the cylinder needles is brought about by the push-out cam 100 which operates against the upper ends of the cylinder pattern jacks, throwing the lower ends of the jacks outward and, by the make-up selector lever 102 which engages butts on every other cylinder pattern jack and pushes the lower ends of these jacks back to the needle cylinder. The remaining jacks having their lower ends left in their 55 outer positions have their butts engage the jack raising cam 366 which operates every other jack to raise the corresponding cylinder needle to the clearing level. The needles that are not raised by the pattern jacks are left at the tucking level 60 at which they take yarn but do not place their loops below the latches and to which they were raised by the side cam 40. On the first main rack of the main pattern drum for the make-up or the beginning of the stocking dividing cam 382 70 is inserted part way while over the short butt needles to operate on the long butt needles and carry every other needle beneath the stitch cam 361 so that they will not take the yarns on the first course. This dividing cam 382 carries down 75

only the needles which are left at the tucking level as the needles which are raised by the cylinder pattern jacks pass over the top of cam 382 and take the body yarn at the throat plate. As the 5 selected needles reach the throat plate an auxiliary rack brings the body yarn finger into action. While engaging the long butt needles the cam 382 is inserted all the way by an auxiliary racking movement so as to carry down the short butt 10 needles as they reach the cam. After the needles have been divided by the cam 382 for one complete revolution a raising cam 12^a is inserted to raise the long butt needles which are not raised by the cylinder pattern jacks above the dividing 15 cam 382 so that during the second revolution in which the body yarn is fed all the long butt needles are caused to take the body yarn and the long butt needles which took the body yarn in the first revolution cast off their loops and knit. 20 While the long butt needles are being raised over the top of the cam 382 this cam is withdrawn part way so that the short butt needles will be allowed to pass over the top of the leading stitch cam 381, thus all short butt needles take the body 25 yarn in this second revolution and those short butt needles which took the body yarn in the first revolution cast off their loops and knit. This completes the selavage edge, that is, one revolution of the needle cylinder with alternate needles taking the body yarn followed by one revolution with every needle taking the body yarn and the needles which took yarn during the first revolution casting off their loops and knitting. After 30 the long butt needles are raised during the second revolution the raising cam 12^a is withdrawn from action. At the beginning of the third revolution the dividing cam 382, being only partly withdrawn, begins to draw down the first long butt needles in order to withdraw every other long 35 butt needle from action and while engaging the long butt needles the cam 382 is moved inwardly to engage the alternate short butt needles left at the tucking level. At this time the dial carried-transfer bits T are advanced by the knitting 40 point and the body yarn is drawn, by the needles which take it, over the transfer bits T so that during this revolution the needle cylinder alternate needles draw loops of the body yarn and cast off the loops previously taken and the bights 45 of the body yarn between the needles which drew loops are taken and held by the transfer bits T until the completion of the welt, the transfer bits being drawn back to an intermediate position 50 immediately upon taking the bights of the body yarn.

Where the cutter and clamp for the rubber yarn are not used the rubber yarn guide 110 is dropped into feeding position just before the leading long butt needle reaches the position of the elastic yarn 60 guide 110 in the third revolution of the needle cylinder. This places the rubber yarn in feeding position in advance of the projecting transfer bits in the third revolution and permits the rubber yarn being engaged with the needles below the 65 latches thereof in the third revolution. Inasmuch as the rubber yarn extends to the preceding stocking the rubber yarn is drawn around the leading long butt needle and carried along thereby as shown in Fig. 15.

70 Prior to the beginning of the third revolution a cam 14 is operated by suitable means from the main pattern drum to a position in which it engages the butts of all needles, beginning with the first long butt needle and lowers them so that the needles which do not have their jacks raised

by cam 386 will not be raised to a level in which they would take the rubber yarn R when the rubber yarn guide 110 is lowered at the beginning of the third revolution. The selected needles which have their jacks raised by the cam 386 are 5 raised to a level which brings the rubber yarn below their latches. The rubber yarn R is cast off at the throat plate and is not, at this time, knit in or interlaced with the fabric but, as shown in Figure 16, rests on the fabric loops in back 10 of the cylinder needles N and below the transfer bits T, the presser plate 160 holding the yarn in this position and preventing it from getting above the transfer bits T. At this time the loops formed will be as shown in Figure 17, in which 15 the first course a of the body yarn Y is interlooped at alternate needles with the second course b while the needles which had been brought into action during the knitting of the second course only and are withdrawn during the knitting of 20 the third course c retain their loops for interlooping with the fourth course d. The fourth course d will also be interlooped at alternate needles with the third course c which has been interlooped in the same wales with the second course b. 25 The rubber yarn R is not interlooped with any of the other courses but rests freely on the fabric loops and the transfer bits T retain the loops taken in the second course b. The dividing cam 382 may be kept in action for approximately a 30 course and a half after the rubber yarn finger is lowered in order to prevent imperfect work which might occur if all the needles were brought into action immediately after the transfer bits T are withdrawn with the bights they hold. While the 35 cam 382 is in the rubber yarn R is laid in front of the needles and below the latches but is not interlaced therewith so that when cast off at the knitting point it is merely laid on the loops, as shown in Figure 17. The dividing cam 382 when 40 withdrawn is withdrawn in two steps after the long butt needles have passed but before the cam 382 is withdrawn the cam 12 is inserted at the beginning of the long butt needles and the sinker cam 189 is inserted, and, simultaneously 45 with the insertion of the cam 12 to its extreme inner position, the thrust rod 462 has caused the push-off cam 244 which cooperates with the jack raising cam 366 to move to its operative position. The push-off cam 244 forces the jacks from the 50 cam 366 and insures that no needle will be raised by its pattern jack above the level of the cam 12 so that the needles thus raised to take the rubber yarn are operated by the cam 12 to draw down the rubber yarn R over the knocking-over 55 surfaces of the sinkers w while the remaining needles, when raised with the selected needles to take the body yarn, are raised in front of the rubber yarn, thus interlacing the rubber yarn in front and in back of the adjacent needles, as shown in Fig. 13, so that when the rubber yarn is cast off at the knitting point it is interlaced between the loops of the fabric forming the welt. After the loops are drawn off the elastic yarn and before the needles are raised to take the body 60 yarn Y the sinkers are moved inwardly to hold down the elastic yarn as the needles are raised. This operation continues throughout the knitting of the welt, the rubber yarn being introduced in each course thereof.

70 Where the cutter and clamp are used the rubber yarn guide 110 is kept out of action during the knitting of the selvage and for one or more courses thereafter until a convenient main rack serves to operate the rubber yarn guide into feed- 75

ing position. At this time the push-off cam 244 has been inserted and the raising of alternate needles is taking place so that the rubber yarn R may be taken by alternate needles, drawn over 5 the sinkers and positioned for interlacing with the needles, as shown in Figure 14. At this time, that is, after four or more courses the relation of the rubber yarn to the needles is identical whether the cutter and clamp are used or not. 10 The feeding of the elastic yarn continues through the transfer of the loops held by the transfer bits T to the needles opposite the bits upon the completion of the welt, this operation being shown in Figure 21 where the rubber yarn R is taken and 15 drawn down by the needles N below the nebs of the sinkers before the transfer bits are pushed out to permit the needles opposite thereto to be raised to take the loops of the body yarn from the transfer bits T in the usual manner. 20 Upon the completion of transfer of the loops from the transfer bits T to the needles the loops are as in Figure 23 in which the loops of the course c, which were held by the transfer bits T and which are shown as being cast off from 25 the needles by which they were taken, are inter-looped with the loops of the course 1 then being formed. The rubber yarn R is interlaced with the needles, as in the previous courses, and when cast off is interlaced with the loops of the transfer course, but is not knit therewith. Upon completion of the transfer the transfer bits are withdrawn by an auxiliary racking movement which also throws out the make-up selector lever 102 30 and causes the reader cams 765, operated from the auxiliary pattern drum 106, to be placed in action. As shown in Fig. 1 the reader cams used are the two lower cams 765 operated by the auxiliary pattern drum 106 and these reader cams select jacks to cause three of every four needles 35 to be raised to take and draw down the rubber yarn. Thus when all the needles are raised to take the body yarn Y the intervening needles are raised in front of the rubber yarn while the needles which drew down the elastic yarn pass up 40 in back of the elastic yarn thus interlacing the rubber yarn in front of three and in back of one of each four needles and the elastic yarn is cast off by each group of three needles that took it as a single bight that is not knitted or interlooped 45 with the body yarn. The needles which take the elastic yarn are raised only in every fourth course during the knitting of the top and the dial is raised from the position it had during the knitting of the welt in order that there may be clearance 50 between the fabric and the dial to permit of the rubber yarn extending across the needle circle 55 during the revolutions in which the yarn is not taken.

During the knitting of the stocking top the 60 sinker cam 312 is also inserted so as to lengthen the loops in the wales on each side of the tying-in needle or needle in back of which the rubber yarn is placed when interlaced with the needles. Upon completion of the top or of the desired 65 length of top with elastic therein the elastic yarn guide and the cams 12, 14, 244, 189 and 312 and the reader cams 765 are withdrawn and the knitting of the remainder of the stocking proceeds in the usual manner with others of the reader 70 cams 765 (not shown) being used for patterning in the usual manner, if desired. Where a cutter and clamp mechanism is provided the elastic yarn is taken by the clamp and cut, to be held thereby until it is again presented to the needles during the knitting of the welt of the next stocking. 75

Where the cutter and clamp mechanism is not used the elastic yarn connects the stockings in "string work" as they are knit until severed manually in order to separate the stockings.

As shown in Fig. 29, a stocking welt and top made in accordance with this invention has a double-walled welt W united with the stocking top in the knitting thereof, both the welt and the stocking top being of plain fabric while between the walls of the welt, but not secured thereto, lie one or more courses of the elastic yarn R. Interlaced with the wales of each course of the welt W and in the transfer course, and one or more courses of the stocking top S immediately following the transfer course, are other courses 15 of elastic yarn and while the elastic yarn has been shown and described as placed in front of and in back of alternate needles the elastic yarn may be interlaced in different arrangements with respect to the needles. Below the courses above 20 described the elastic yarn is introduced into every fourth course of the stocking top for as many courses as desired or throughout the length of the top, the elastic yarn as shown being placed in front of three adjacent needles and in back 25 of the fourth needle of every four needles of the courses in which it is introduced, the corresponding needles being in the same wales in each of such courses so that a straight rib effect is secured. 30

The particular fabric shown and described is not claimed herein as it is claimed in application Serial No. 184,890, filed January 13, 1938.

What is claimed is—

1. In a circular knitting machine having independent needles and a dial having knitting instrumentalities for holding and transferring loops of a body yarn in the knitting of a welt, means for feeding an elastic yarn to said needles and means for operating said needles to interlace said elastic yarn with the needles but not knit the elastic yarn thereon during the knitting of the welt and the transfer of loops of the welt from the dial knitting instrumentalities to the needles. 35

2. In a circular knitting machine having independent needles and a dial having knitting instrumentalities for holding and transferring loops of a body yarn in the knitting of a welt, means for feeding an elastic yarn to said needles and means for operating said needles to interlace said elastic yarn with the needles but not knit the elastic yarn thereon during the knitting of the welt, the transfer of loops of the welt from the dial knitting instrumentalities to the needles and the knitting of the stocking top. 40

3. In a circular knitting machine having independent needles and a dial having knitting instrumentalities for holding and transferring loops of a body yarn in the knitting of a welt, means for feeding an elastic yarn to said needles, means for operating said needles to interlace said elastic yarn with the needles but not knit the elastic yarn thereon during the knitting of the welt, the transfer of loops of the welt from the dial knitting instrumentalities to the needles and the knitting of the stocking top and means for selecting the needles for tying-in the elastic yarn. 50

4. In a circular knitting machine having independent needles and a dial having knitting instrumentalities for holding and transferring loops of a body yarn in the knitting of a welt, means for feeding an elastic yarn to said needles; means for operating said needles to interlace said elastic yarn with the needles but not knit the elastic 55

- yarn thereon during the knitting of the welt, the transfer of loops of the welt from the dial knitting instrumentalities to the needles and the knitting of the stocking top and means for selecting different groups of needles for tying-in the elastic yarn in the fabric of the welt and top.
5. In a circular knitting machine having independent needles and a dial having knitting instrumentalities for holding and transferring loops of a body yarn in the knitting of a welt, means for feeding an elastic yarn to said needles, means for operating said needles to interlace said elastic yarn with the needles but not knit the elastic yarn thereon during the knitting of the welt, the transfer of loops of the welt from the dial knitting instrumentalities to the needles and the knitting of the stocking top, means for selecting the needles for tying-in the elastic yarn in the welt and separate means for selecting the needles for tying-in the elastic yarn in the top.
10. In a circular knitting machine having independent needles and a dial having knitting instrumentalities for holding and transferring loops of a body yarn in the knitting of a welt and means for feeding an elastic yarn to said needles, means for operating said needles to interlace said elastic yarn with the needles but not knit the elastic yarn thereon during the knitting of the welt, the transfer of loops of the welt from the dial knitting instrumentalities to the needles and the knitting of the stocking top, means for selecting needles for tying-in the elastic yarn and means for changing the needle selection.
15. In a circular knitting machine having independent needles and sinkers arranged for knitting plain fabric, means for feeding an elastic yarn against the shanks of selected needles, means operating the needles to interlace the elastic yarn with the needles, means feeding a body yarn to all the needles, means advancing sinkers adjacent non-selected needles to lengthen the loops at such needles and means operating all the needles to knit the body yarn and cast off the elastic yarn from the selected needles.
20. In a circular knitting machine having independent needles and sinkers arranged for knitting plain fabric, means for feeding an elastic yarn against the shanks of selected needles, means operating said selected needles to measure loops of the elastic yarn over the knocking-over surfaces of said sinkers, means operating the needles to interlace said elastic yarn with the needles, means feeding a body yarn to all the needles and means operating the needles to knit said body yarn and to cast off the elastic yarn from the selected needles.
25. In a circular knitting machine having independent needles and sinkers arranged for knitting plain fabric, the steps of feeding the elastic yarn against the shanks of selected needles, thereafter catching the elastic yarn in the throats of the sinkers and drawing bights of said elastic yarn between the needles, subsequently releasing the bights, clearing the latches of the selected needles, feeding a body yarn to all the needles and knitting said body yarn on all needles and casting off the elastic yarn from the selected needles to tie-in the elastic yarn in the sinker wales adjacent non-selected needles.
30. In a circular knitting machine having independent needles and sinkers arranged for knitting plain fabric, the steps of feeding the elastic yarn against the shanks of selected needles, measuring loops of the elastic yarn on the knocking-over surfaces of the sinkers, holding the yarn by the sinkers and raising the selected needles, feeding a body yarn to all needles, knitting said body yarn on all needles and casting off the elastic yarn from the selected needles.
35. In a method of incorporating elastic yarn in a stocking being knit on a circular knitting machine, the steps of feeding the elastic yarn against the shanks of selected needles, operating the remaining needles during the knitting of the welt, transfer and stocking top to interlace said elastic yarn with the needles, feeding and knitting a body yarn on all needles in all courses throughout the welt, transfer and top and casting off said elastic yarn from the selected needles with the body yarn.
40. In a method of incorporating elastic yarn in a fabric being knit on a circular knitting machine, the steps of feeding the elastic yarn against the shanks of selected needles, measuring loops of the elastic yarn on the knocking-over surfaces of the sinkers, feeding a body yarn to all needles, operating the sinkers adjacent non-selected needles to lengthen the loops of the body yarn at such non-selected needles, knitting the body yarn on all needles and casting off the elastic yarn from the selected needles with the body yarn to tie-in the elastic yarn at the lengthened loops.
45. In a method of incorporating elastic yarn in a fabric being knit on a circular knitting machine, the steps of feeding the elastic yarn against the shanks of selected needles, feeding a body yarn to all needles, operating the sinkers adjacent non-selected needles to lengthen the loops of the body yarn at such non-selected needles, knitting the body yarn on all needles and casting off the elastic yarn from the selected needles with the body yarn to tie-in the elastic yarn at the lengthened loops.
50. In a method of incorporating elastic yarn in a stocking fabric being knit on a circular dial knitting machine, the steps of securing loops of a starting-up course on dial instrumentalities, knitting plain fabric of a body yarn on all needles for a plurality of courses, feeding the elastic yarn against the shanks of selected needles, casting the elastic yarn from the needles during the knitting of one or more courses without engaging the elastic yarn with the fabric, operating the remaining needles during the knitting of a plurality of subsequent courses to interlace the elastic yarn with the needles, casting off the elastic yarn from the selected needles with the body yarn in the knitting of said subsequent courses and transferring the loops from the dial instrumentalities to the needles during the knitting of one of said subsequent courses.
55. In a circular knitting machine having independent needles and sinkers arranged for knitting plain fabric, means for feeding an elastic yarn against the shanks of selected needles, means operating said selected needles to measure loops of the elastic yarn over the knocking-over surfaces of said sinkers, means operating the needles to interlace said elastic yarn with the needles, means feeding a body yarn to all the needles, means advancing sinkers adjacent non-selected needles to lengthen the body yarn loops at such needles and means operating all the needles to knit the body yarn and cast off the elastic yarn from the selected needles.
60. In a circular knitting machine having independent needles and sinkers arranged for knitting plain fabric, means for feeding an elastic yarn against the shanks of selected needles, means operating said selected needles to measure loops of the elastic yarn over the knocking-over surfaces of said sinkers, means operating the needles to interlace said elastic yarn with the needles, means feeding a body yarn to all the needles, means advancing sinkers adjacent non-selected needles to lengthen the body yarn loops at such needles and means operating all the needles to knit the body yarn and cast off the elastic yarn from the selected needles.
65. In a circular knitting machine having independent needles and sinkers arranged for knitting plain fabric, means for feeding an elastic yarn against the shanks of selected needles, means operating said selected needles to measure loops of the elastic yarn over the knocking-over surfaces of said sinkers, means operating the needles to interlace said elastic yarn with the needles, means feeding a body yarn to all the needles, means advancing sinkers adjacent non-selected needles to lengthen the body yarn loops at such needles and means operating all the needles to knit the body yarn and cast off the elastic yarn from the selected needles.
70. In a circular knitting machine having independent needles and sinkers arranged for knitting plain fabric, the steps of feeding the elastic yarn against the shanks of selected needles, measuring loops of the elastic yarn on the knocking-over surfaces of the sinkers, holding the yarn by the sinkers and raising the selected needles, feeding a body yarn to all needles, knitting said body yarn on all needles and casting off the elastic yarn from the selected needles.
